UNITED STATES PATENT OFFICE.

WARREN T. GREEN, OF ST. LOUIS, MISSOURI, ASSIGNOR TO THE MENGEL COMPANY, OF LOUISVILLE, KENTUCKY, A CORPORATION OF NEW JERSEY.

DESIGN FOR A WHEEL-FORK FOR CHILDREN'S VEHICLES.

58,144.

Specification for Design.

Patented June 14, 1921.

Application filed January 31, 1921. Serial No. 441,477. Term of patent 14 years.

To all whom it may concern:

Be it known that I, WARREN T. GREEN, a citizen of the United States, residing at St. Louis, State of Missouri, have invented a new, original, and ornamental Design for a Wheel-Fork for Children's Vehicles, of which the following is a specification, reference being had to the accompanying drawing forming part thereof.

The figure is a perspective view of a wheel fork for children's vehicles showing my new design.

I claim—

The ornamental design for a wheel fork for children's vehicles, as shown.

WARREN T. GREEN.
